UNITED STATES PATENT OFFICE.

PETER E. LONG AND EDWARD R. CORNWELL, OF POCATELLO, IDAHO.

CLIP.

Application filed June 6, 1922. Serial No. 566,370.

To all whom it may concern:

Be it known that we, PETER E. LONG and EDWARD R. CORNWELL, citizens of the United States, residing at Pocatello, in the 5 county of Bannock and State of Idaho, have invented a new and useful Clip, of which the following is a specification.

This invention relates to a paper clip, one of its objects being to provide a clip of improved construction whereby papers when gripped thereby will be held together securely, the configuration of the clip being such that pressure will be exerted thereby upon the papers both at the end of the clip 15 and at a point between the ends, thus preventing the papers from slipping out of the clip.

Another object is to provide a clip so shaped that when papers are held assembled 20 thereby, there is no danger of other papers becoming engaged by the clip inadvertently as is commonly the case with other clips generally in use.

With the foregoing and other objects in 25 view which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings the preferred form of the invention has been 35 shown.

In said drawings—

Figure 1 is a plan view of the clip.

Figure 2 is a side elevation thereof.

40 Figure 3 is a section on line 3—3, Figure 1.

Referring to the figures by characters of reference it will be noted that the clip is made in a single length of wire or other 45 spring material bent to form a side portion 1, end arcuate portions 2 and 3, and intermediate arcuate portion 4, a side portion 5, and outer and inner parallel terminal portions 6 and 7. As shown particularly in 50 Figures 2 and 3 the arcuate portion 3 is

obliquely disposed relative to the plane occupied by the side portion 1 and the terminal portion 6 and the arcuate portion 4 is likewise obliquely disposed relative to said plane although inclined oppositely to 55 the portion 3 so that the two arcuate portions 3 and 4 converge toward said plane. The arcuate portion 4 is of less length from side to side than the portion 3 so that it can project between the side portion 1 and the terminal portion 6. These arcuate portions 3 and 4, which constitute gripping means, are preferably flattened as shown so as to terminate in blunt gripping edges 8 and 9, the two arcuate portions converging 60 toward the edge 9. The side portion 5 is necessarily inclined relative to the plane occupied by the side portion 1 and the terminal portion 6, said side portion 5 and the terminal portion 7 occupying the same inclined plane. 65

The two terminal portions 6 and 7 terminate at approximate the same distance from the arcuate portion 2, these terminals being arranged substantially in the same 70 plane with the adjacent portions of the sides 1 and 5.

When it is desired to use the clip the papers to be held are inserted over the arcuate portion 3 and under the arcuate portion 4 and are then forced back so as to shift the terminals of the parts 6 and 7 out of their normal plane. Thus the papers will be gripped tightly by the blunt edges 8 and 9 and by the free ends of the terminal 80 portions 6 and 7 and said papers will be held together properly. Furthermore there is no danger of other papers becoming inadvertently inserted into the clip. The free ends of the terminals 6 and 7 will tend 85 to bite into the paper to hinder the withdrawal of the clip therefrom.

What is claimed is—

A clip formed in a single length of resilient material bent to provide side portions 95 connected at one end, an intermediate arcuate portion at the other end of one of the side portions merging into a terminal portion, and an arcuate end gripping portion at the other end of the other side portion 100

and terminating in a terminal portion, said intermediate arcuate portion and the arcuate end gripping portion being obliquely disposed and converging toward the gripping edge of the intermediate arcuate portion.

In testimony that we claim the foregoing

as our own, we have hereto affixed our signatures in the presence of two witnesses.

PETER E. LONG.

EDWARD R. CORNWELL.
